UNITED STATES PATENT OFFICE.

GEORGE W. KING, OF MARION, OHIO, ASSIGNOR TO THE MARION STEAM SHOVEL COMPANY, OF MARION, OHIO, A CORPORATION OF OHIO.

EXCAVATING-DIPPER.

No. 856,707.

Specification of Letters Patent.

Patented June 11, 1907.

Application filed January 7, 1907. Serial No. 351,033.

To all whom it may concern.

Be it known that I, GEORGE W. KING, a citizen of the United States, residing at Marion, in the county of Marion and State of Ohio, have invented certain new and useful Improvements in Excavating-Dippers, of which the following is a specification, reference being had therein to the accompanying drawings.

- 10 The present invention relates to excavating dippers of the type commonly employed with steam shovels and dredges. In dippers of this character the front is ordinarily made in one piece with the side portions of the dipper and consists of comparatively thin sheet metal. This sheet metal front is provided at its upper edge with a lip or mouth piece which is secured thereto and is of greater thickness than the body portion of the front.
- 15 This sheet metal front is not of sufficient strength and rigidity to withstand the strain imposed upon it and it is necessary to provide the same with large and heavy teeth, the inner shank of which must extend to the bottom of the bucket in order to stiffen and strengthen the front sufficiently to enable it to withstand the strain placed upon it. These teeth, when they become badly worn, must be discarded and replaced by new
- 20 teeth, and, as the same are constructed of a high grade steel, the expense of thus replacing the teeth is considerable.

The object of the present invention is to provide a dipper of this character having a comparatively heavy front which is detachably secured to the side portions of the dipper and in which the lip will be formed integral with the front which is formed of a hard, strong steel adapted to withstand a great deal of wear and of such strength and stiffness as to permit the use of comparatively small short teeth.

With this object in view the invention consists in certain novel features of construction to be hereinafter described, and then more fully pointed out in the claims.

In the accompanying drawings, Figure 1 is a top plan view of a dipper embodying my invention; Fig. 2 is a front elevation of the same; Fig. 3 is a side elevation thereof; and Fig. 4 is a bottom plan view of the same.

In these drawings, I have illustrated my invention as embodied in one form of dipper which consists of side portions 1 and a back

2, and is provided with a bottom 3 carried by suitable arms 4 which are hinged at 5 to the back 2 of the dipper, and provided with suitable locking mechanism, as shown at 8, whereby the bottom can be secured in its closed position and readily released when it is desired to discharge the contents of the dipper. The side portions 1 are provided with suitable brackets 6, to which are hinged the ends of the bail 7. That part of the dipper so far described is of ordinary construction and forms no part of the present invention.

The front 9 of the dipper is formed, preferably by casting, of hard, strong steel, such as manganese steel, which possesses great strength and stiffness. This front piece has its side portions 10 turned at substantially right angles thereto and secured to the side portions 1 of the dipper by means of suitable bolts or rivets 11, whereby the same can be readily detached therefrom when it is desired to renew the same. The upper edge or lip 12 of the front is formed integral with the body portion thereof which is of such strength and rigidity as to permit the use of comparatively small teeth 13, which are provided with shanks 14 extending on opposite sides of the lip 12 and rigidly secured thereto by means of suitable rivets or bolts 15. The lip 12 is provided with a series of recesses 16 formed in the upper edge thereof and adapted to engage the body portions of the teeth 13 and hold the same against lateral movement relatively to the front 9 of the dipper. The teeth are further strengthened and held against movement by means of suitable projections 17 rigidly secured to the front 9 near the end of one of the shanks 14 and on the opposite sides thereof. The front 9 is also provided near its lower end with an apertured plate 18 which is adapted to coöperate with the locking mechanism 8.

The dipper herein described can be provided at a comparatively small cost and the parts which are subjected to wear are of such strength and hardness as to enable them to withstand a great deal of wear and to last for a long time, and further, the portion which is subjected to wear is detachably secured to the body portion of the dipper, whereby it can be readily removed and renewed in case it does become worn or broken. Further, the front is of such strength and

stiffness as to permit the use of relatively small, light teeth which can be readily removed and renewed when worn. As the wear on these teeth comes principally upon the point the small teeth employed with the present dipper will last substantially as long as the large heavy teeth used in the ordinary form of dipper, thereby greatly reducing the cost of renewing these teeth.

I wish it to be understood that I do not desire to be limited to the exact details of construction shown and described, for obvious modifications will occur to a person skilled in the art.

Having thus fully described my invention, what I claim as new and desire to secure by Letters Patent, is:—

1. A dipper of the character described, comprising a body portion and a front detachably secured thereto, substantially as described.

2. A dipper of the character described, comprising a body portion, a front detachably secured to said body portion, and a lip formed integral with said front, substantially as described.

3. A dipper of the character described comprising a body portion, and a front of

cast metal secured thereto, substantially as described.

4. A dipper of the character described comprising a body portion, a front of cast metal, and teeth secured to the upper edge of said front, substantially as described.

5. A dipper of the character described comprising a body portion, a front of hard rigid steel detachably secured thereto, teeth secured to the upper end of said front and having shanks extending on the opposite sides thereof, and projections on said front engaging the opposite sides of said shanks, substantially as described.

6. In a dipper of the character described, a body portion comprising side walls, back and bottom portions, a front of relatively heavy casting detachably secured to said side walls, a lip formed integral with said front, and relatively small teeth detachably secured to said lip, substantially as described.

In testimony whereof, I affix my signature in presence of two witnesses.

GEORGE W. KING.
